UNITED STATES PATENT OFFICE.

PAUL STRANGE, OF NEENAH, WISCONSIN, ASSIGNOR TO JOHN STRANGE PAIL COMPANY, OF MENASHA, WISCONSIN, A CORPORATION OF WISCONSIN.

RECEPTACLE.

Application filed April 9, 1924. Serial No. 705,321.

This invention relates to receptacles, such as tubes, pails, firkins and the like, designed for the packing, storage or transportation of various materials or commodities. It has to do particularly with receptacles fabricated of fibrous material, such as paper stock. Due to various characteristics, such as their lesser weight and cost and uniformity of size, receptacles of that type are, to an increasing extent, supplanting wooden receptacles in many uses.

While retaining the advantages of light weight and low cost, it is important that such receptacles possess great strength and stability, in order that the relatively less amount of material in their structure be qualified to withstand the stresses imposed upon them by the weight of the contained material, handling in transportation, and the weight of the receptacles or packages to which they are subjected when stacked in storage. One of the principal objects of the present invention, therefore, comprises certain improvements in the details of construction of such articles, whereby their strength and stability are increased effectively without appreciable increase in weight or the amount of material required or increase in the cost of manufacture.

Another object is the improvement of certain features in the construction of the receptacles which contribute to safety and convenience in the storage and transportation of them by enabling their being stacked with security.

Still another object is the simplification of the manufacture of articles of the sort described.

Other and further objects of the invention will be pointed out hereinafter, indicated in the appended claims, or obvious to one skilled in the art upon an understanding of the present disclosure. For the purpose of this application I have elected to disclose certain structures, which I present as illustrative of the invention, and are not to be construed as limiting what I purport to secure, short of the true and most comprehensive scope of the invention in the art.

In the drawing forming a part of this specification,

Fig. 1 is a partial sectional elevation taken on the diameter of two firkins or pails, shown in the relationships in which they are customarily stacked in storage and trans-

portation, with one resting on top of the other;

Fig. 2 is a detail in the nature of a sectional elevation through a marginal portion of a receptacle at the junction of the bottom 60 and the side;

Fig. 3 is a detail in the nature of a part sectional elevation of certain apparatus and one of the elements of the receptacle structure, illustrating a step in the forming of 65 the latter;

Fig. 4 is a similar detail illustrating a subsequent step in the manufacture of the receptacle; and

Fig. 5 is a detail in the nature of a magnified section of a wall portion of a receptacle.

The nature of the invention will be understood best by reference to the illustrative disclosure in detail. Referring to the drawing, let it be understood that the reference numeral 10 designates the wall portion of a receptacle, the same being formed of fibrous material such as paper stock, preferably built up of a plurality of layers or laminations. In actual practice, this may be made relatively thin, approximately one-eighth of an inch in a receptacle having a capacity of five gallons or more. It is of certain commercial advantage to have the 75 receptacles of frusto-conical form. The wall portion may be formed after the fashion described in the patent to John Strange, No. 1,198,596, granted September 19, 1916. The smaller end of the body portion is closed 80 by a bottom 11 of similar structure. This bottom is retained against upward movement by a hoop 12 fitting closely within the body portion and contacting at its lower margin the peripheral portion of the bottom. This 85 bottom is retained against upward movement by a hoop 12 fitting closely within the body portion and contacting at its lower margin the peripheral portion of the bottom.

A supporting ring 14 is fitted within the wall portion below the bottom, and contacts the latter below its marginal portion. The hoop 12 and ring 14 preferably are made of the same material as the wall portion, after the fashion described in the patent above mentioned. With this assembly 95 is combined a retaining ring made of sheet metal and formed with the constraining flange 15, the binding flange 16 and the supporting 100 17. The constraining flange is continuous and formed on such radius as to closely encompass the wall portion 10. It is of such depth as to overlap the peripheral margins of the bottom 11 and a portion of 105 110

the height of the hoop 12. The binding flange 16 is of such length as to overlap the bottom margins of the wall portion and the supporting ring 14, while the supporting flange 17 fits closely within the supporting ring and extends up within the same into marginal contact with the lower surface of the bottom 11. At intervals, the supporting flange is provided with short projections 18 extending away from the ring 14. These, together with the marginal portion of the supporting flange, supplement the ring 14 to give increased supporting area for sustaining the bottom 11. The supporting and constraining flanges bear such relationship that the lower part of the wall portion and the ring 14 are supported and confined between them, said flanges conforming respectively to the internal taper of the ring 14 and the external contour of the body portion. At intervals about the receptacle staples 19 are inserted to secure together the constraining flange, the wall portion and hoop 12. The binding flange 16 is traversed by a series of radially extending depressions 20, which are pressed in the metal.

Certain features of the structure, as well as the method of producing it will be understood by reference to Figs. 3 and 4. In the production of the retaining ring, a hoop is first formed from a strip of sheet metal, said hoop being of the approximate diameter of the outer surface of the lower portion of the wall. This hoop is placed on a forming mandrel M and spun over the flange m thereof by means of a suitable spinning roller R. The top of the flange m is transversely serrated to mate with the knurling r of the spinning roller, so that the co-action of the two forms the depressions 20. Inasmuch as the spinning operation folds the marginal portion of the metal hoop inwardly, parts of the metal are forced into puckers or convolutions, which form the projections 18. The ring when thus formed is removed from the mandrel M and fitted on to the lower margin of the receptacle, as above described. If completely formed in the spinning operation, so as to have an accurate fit, the ring may then be secured in place by insertion of the staples 19. If not completely formed in the spinning operation, it may be further shaped, after application to the body, by suitable means S and S'. This operation may be performed in such fashion as to flatten down portions of the projections 18, thus giving the flange 17 an expansive tendency which contributes to the tightness of the assembly. The staples 19 anchor the constraining flange securely in place, opposing any tendency, which may be given it by the expansion of the supporting flange 17, to flare away from the wall portion 10. The resulting structure possesses great strength and rigidity at the important joint between

the bottom and the side wall, all of the component parts being bound positively together and retained in the desired contour by the stiff channel structure resulting from the arrangement of the flanges 15, 16 and 17.

As heretofore employed, a top closure 21 is provided for the receptacle, the same having the depending flange 22 which receives the upper marginal portion of the wall 10. A pair of stiffening members 24 are disposed in crossed relationship on diameters of the top closure, being secured to the latter by suitable means 25. Over these are stretched wires 26 which are secured at their ends to loops in a girth wire 27 encompassing the receptacle. In the storage of packaged commodities, it is important that the packages lend themselves conveniently to stacking. In the present improvements advantage is contributed by the arrangement of the retaining ring with its radial bottom depressions 20 for co-operation with the wires 26, as such affords a form of connection between superimposed packages which facilitates their being stacked in straight piles, prevents their rotation upon one another and prevents their sliding off one another. The corrugation of the binding flange by the depressions 20 also serves to stiffen it transversely and thereby aid in retaining the shape of the supporting flange.

Certain improved features of the wall structure are illustrated in Fig. 5. As illustrated, the wall may be made up of the three laminations 10^a, 10^b and 10^c, as above described. To these, on the interior, is added a composite lamination formed of sheets 10^d of flexible material, such as paper, and an intermediate binder stratum 10^e of waterproofing adhesive material, such as asphalt. In the manufacture of the receptacle, the composite lamination is first made up in sheets, which sheets are then cut to the proper shapes and combined with the other laminations. The waterproofing layer 10^e is effective to prevent or retard the penetration of moisture into the receptacle through the walls thereof, or into the laminations 10^a, 10^b and 10^c from the interior of the receptacle.

I claim:

1. In a receptacle, the combination of a conic wall portion, a bottom closure at one end thereof, an internal hoop conforming to the inner contour of the wall portion and retaining the bottom closure against upward movement therein, a supporting ring within the wall portion below the closure and supporting the same against the internal hoop, a binding flange extending across the adjacent margins of the ring and wall portion, a supporting flange extending upwardly from the binding flange inside the ring and into contact with the bottom closure, a constraining flange extending up-

wardly from the binding flange on the outside of the wall portion, and means securing the constraining flange to the wall portion and internal hoop above the bottom closure, whereby the internal hoop is stayed against movement upwardly in the body portion by the binding flange and the constraining flange.

2. In a receptacle, the combination with 10 a conic wall portion and bottom closure, of a supporting ring within the former below the latter, an internal hoop within the wall portion above the bottom closure and having contact therewith, a channel-shaped retaining ring enveloping the lower margin of the wall portion and supporting ring, said retaining ring being provided with inward projections contacting the bottom closure to support the same, and means securing 20 the retaining ring to the body portion and internal hoop above the bottom closure.

3. In a receptacle, the combination with a wall portion and a top closure including radial retaining wires, of a retaining ring 25 enveloping the lower margin of the wall portion and secured thereto, said retaining ring being provided with radially extending depressions for engagement with closure-retaining wires of similar receptacles.

4. In a receptacle, the combination with 30 a wall portion and a bottom closure, of a retaining ring enveloping the margin of the wall portion below the bottom closure, said retaining ring having a constraining flange encompassing the wall portion over the margin of the bottom closure, a binding flange traversing the lower margin of the wall portion, and a supporting flange disposed within the wall portion to furnish support for 35 the bottom closure, said binding flange being transversely corrugated.

5. A receptacle structure comprising a conic body portion, an enclosure within the same, hoops seated against the internal wall of the body portion above and below the closure and overlapping the top and bottom surfaces thereof, a restraining ring secured to the body portion and enveloping the edge thereof, said restraining ring supporting the lower hoop against movement downwardly 40 on the body portion, and means securing the upper hoop to the restraining member whereby the latter functions as a stay to hold the upper hoop against movement upwardly in the body portion.

In testimony whereof I have hereunto signed my name.

PAUL STRANGE.

CERTIFICATE OF CORRECTION.

Patent No. 1,663,618.

Granted March 27, 1928, to

PAUL STRANGE.

It is hereby certified that error appears in the printed specification of the above numbered patent requiring correction as follows: Page 3, line 43, claim 5, for the word "enclosure" read "end closure"; and that the said Letters Patent should be read with this correction therein that the same may conform to the record of the case in the Patent Office.

Signed and sealed this 15th day of May, A. D. 1928.
